BINDING MEANS

Ralph M. Hibbs, Philadelphia, Pa., assignor of
fifty per cent to Stephen E. Lewis, Middleport,
N. Y.

Application January 10, 1936, Serial No. 58,573

4 Claims. (Cl. 93—1.1)

This invention relates to means for binding together superposed sheets of flexible material such as paper, Cellophane, metal foil, etc., without requiring the use of stapling devices or pins, or fastening elements extraneous of the flexible material itself.

In the prior art devices have been suggested for causing flexible materials, such as paper, to be tacked or bound together without the use of adhesives, metal clamps or other binding elements, but in all those prior art devices, the devices have taken the form of intermeshing gear wheels, such devices being open to a number of objectionable features. In the first place, such devices are much more complicated than should be necessary for the operation, requiring a number of parts and adjustments. Unless some means are provided for permitting spacing of the gear wheels one from the other, the pressures exerted upon the superposed sheets of flexible material cannot be regulated to allow for variation in thickness of the flexible material sheets, or in the number of sheets to be bound together. Where the device is constructed to permit such regulation, as by means of spacing elements, spring members, etc., the number of parts is materially increased, the cost of the device is greatly raised, and the necessity for adjustment is constantly present. Furthermore in such prior art devices utilizing gear wheels or related elements, the line of impaction of the sheets is necessarily extended continuously from edge to edge of the flexible material, and could not be localized as desired at any particular point on the surface of the flexible sheets.

Among the objects of the present invention, there is included impacting means for causing superposed sheets of flexible material to be bound together, without requiring the use of stapling or other binding devices extraneous of the flexible material itself.

Other objects include such impaction devices of simple construction and inexpensive manufacture, enabling the impaction to be located as desired at any particular point on the surface of the flexible sheet.

Further objects include articles of manufacture consisting of superposed sheets of flexible material bound together without adhesive or binding devices other than the material from which the flexible sheets themselves are composed, in which the impaction is at a localized point on such flexible sheets.

Still further objects and advantages of the present invention will appear from the more de-

tailed description set forth below, it being understood, however, that this more detailed description is given by way of illustration and explanation only, and not by way of limitation, since various changes therein may be made by those skilled in the art without departing from the scope and spirit of the present invention.

In connection with that more detailed description there is illustrated in the accompanying drawing, in

Figure 1, a side elevation of a binding device constructed in accordance with the present invention; in

Figure 2, a vertical lateral section through the device of Figure 1; in

Figure 3, an end elevation of the device shown in Figure 1; in

Figures 4, 5 and 6, various forms of impaction dies; and in

Figures 7, 8 and 9, side elevations of the dies respectively of Figures 4, 5 and 6.

In accordance with the present invention, the sheets of flexible material are caused to be bound together by impacting the sheets together, and slightly distorting the area of impaction without mutilating or tearing the flexible material, so that they remain bound together. Desirably such impaction or binding of the sheets of flexible material is effected by means of two members, such as racks, which are mounted in such a way that superposed sheets of flexible material may be interposed between the racks, and then the racks impacted toward each other to cause a serrated distortion of the flexible material, interlacing the fibers of the several sheets together, so that they remain bound together when removed from the crimping device.

Referring to the form of device illustrating the invention as shown in the drawing, the device may take the form of the usual type of paper stapling device, eliminating, however, any necessity for stapling or binding elements. In this type of construction, which is illustrated in the drawing, there desirably is a base member 1, having foot portions 2, 2 provided with cushioning members 3, 3, made of rubber, felt, or similar material to protect the surface of the desk or other article of furniture on which the device is used, and also desirably to prevent slippage of the device on such surface.

Desirably at one end of the base member 1, an upwardly projecting shoulder 4 is provided, having a spring-receiving recess 5, further described below. The shoulder portion 4 has a reduced end 6, the sides of the shoulder portion

having been cut away to provide such reduced portion 6, and to produce diagonally formed ledges 7, 7, extending at their outer ends 8 to substantially horizontal position to form a seat.

5 The opposite end of the base member 1 carries a recess 9 adapted to receive the impaction member or die 10, which may be welded in position, or held in place by removable elements, such as bolts, etc., or in any other desired way. For example, the side walls of the recess 9 may be given a slight draft and the die 10 provided with side walls having a coacting draft, so that the die 10 may be slipped into position in the recess 9.

10 An impacting or percussion arm 11, provided with side walls or webs 12, 12 produces a substantially U-shaped arm, the space between the side or web portions 12, 12 being sufficient to enable the arm to be placed over the reduced end 6 of the shoulder portion 4 of the base 1. Perforations 13 near the end of each side wall 12, 12, are adapted to align with a perforation 14 in the reduced end portion 6 of the projection 4 of the base 1, and a bolt 15 passed through the perforations 13, 13 on the arm 11, and the perforation 14 on the reduced portion 6 serve to hold the arm in position with respect to the base member, the ends of the bolt 15 desirably being swaged over to prevent separation of the parts or their working loose. Any other means of securing the members together may, of course, be utilized other than the bolt referred to.

15 One end 16 of the arm 11 forms a wall portion closing the U-shaped channel in the arm 11, and serves also to hold the spring member in position. In the normal retracted position of the arm 11, the lowermost edge 17 of the end wall 16 rests against the seat 8 on the projection 4 of the base portion 1. To maintain the arm in such normally retracted position, a spring 18, which may be of the ordinary leaf type, is positioned within the U-shaped channel of the arm 11, one end 19 of the spring being placed in the recess 5 of the projection 4 on the base 1, while the other end rests against a stop 20 formed on the inner surface of the arm member 11, the reduced end portion 6 on the projection 4 of the base 1 coacting with the wall portions of the arm member 11, preventing displacement of the spring. The spring 18 normally tends to hold the arm portion in retracted position as shown in Figure 1 with respect to the base portion 1.

20 The other end of the arm 11 is desirably provided with a head portion 21 having a recess 22 for reception of a die or impaction member 23, which may be secured in position in the head member 21 in a manner strictly analogous to that described above for the die member 10. The die members 10 and 23 are mounted so that their respective toothed portions 24 and 25 intermesh when the arm 11 is given an arcuate motion downward about the pivoting bolt 15. A hand portion 26 may be mounted on the head portion 21 for receiving the impact from the hand for operating the device.

25 As illustrated, the die members 9 and 23 are desirably provided with toothed portions 24 and 25 respectively, adapted to intermesh, but any other form of intermeshing elements may be utilized. The toothed members are simple to produce, and produce an effective result. The teeth, as shown in Figures 4 to 9, may be of relatively sharp contour and of a depth so that upon impaction of the two die members (upper and lower) together, the fibers of the flexible material, or of the metal, are distorted sufficiently to inter-

bind the sheets together—but the depth or spacing of the teeth should not be sufficient to cause tearing or other mutilation of the flexible material. The upper and lower dies, such as 10 and 23, are mirror images of each other, so that they will intermesh when brought together. As shown in Figures 4 and 7, such die members, the lower die only being illustrated, may take the form of a base portion 30 having a projecting rack portion 31 carrying the teeth 24 having 10 rounded or bevelled corners 34. These dies, however, may be given any shape or contour desired to produce a corresponding variation in the type of impacted area on the flexible sheets, and this may, for example, be given any geometric figure, 15 letter or numeral configuration, among which may be mentioned an annulus, circle, crescent, triangle, square, etc., or any desired letter or numeral. Illustrating the variation in the form of toothed surface that may be utilized in this 20 connection, Figures 5 and 8 show a die member 10' having toothed members 24', in which the teeth are serrated, as shown at 32. The die 10'' member of Figures 6 and 9 shows the toothed members 24'' arranged in the form of the letter 25 A. Of course, a series of letters may be placed on the die, if desired, or a series of numerals utilized in this way to identify letters or papers or other flexible sheets coming from a particular origin. And if desired a series of different dies 30 may be utilized with any particular device constructed in accordance with the present invention.

25 The device is readily assembled, the arm being placed in position over the base member and held thereto by means of the pivotal bolt 15. In use the superposed sheets of flexible material may be placed in the space between the die members 10 and 23 when the device is in the normal retracted position shown in Figure 1, and then by 40 an impact or percussion blow against the handle portion 26, the dies are forced together to produce an impaction in the flexible material, and to cause the latter to hold together. The arcuate motion of the head member 21 carrying the upper die 23 serves to localize the impaction or 45 percussion, and to accelerate the binding of the papers together.

50 The elements, such as the arm and base, may be made from any desired metal, and either as 50 castings, die castings or metal stampings, bars, etc. The position of the pivotal bolt 15 may be utilized to determine the arcuate movement of the arm 11 and the upper die 23, and raising or lowering the position of the bolt or pin 15 will 55 increase or reduce the arc of moving and the undercutting which is obtained, permitting adjustment depending on the number of sheets of material to be bound together, or the thickness or degree of toughness of such sheets, etc.

55 Since the sheets are bound together by the percussion or impact delivered to the hand portion 24, the degree of binding of the sheets may be determined by the force of the impacting blow. If it is desired to bind the sheets together 60 only temporarily, a lighter blow will be sufficient to hold the papers together, enabling them, however, to be separated when desired without destruction of the flexible material, such as paper, itself. A heavier blow, however, may be utilized 65 to cause substantially permanent attachment of the sheets of superposed flexible material, so that they cannot be segregated without actual tearing of the paper material or disintegration of the sheet material. Where the heavier blow for 70

more or less permanent attachment is utilized, any attempt to separate the sheets will immediately show that they have been tampered with, and thus secure against the segregation of sheets 5 or the substitution of one sheet for another. While the invention has been particularly described and is very useful in connection with securing together sheets of paper, any other sheets 10 of flexible material may be treated in the same way, as, for example, Cellophane, light metals, etc., the only requirement being that the material exhibits sufficient strength to enable it to take the seal produced in accordance with the present invention.

15 It will be seen that because a percussion or impacting die is utilized, such die may be made of any desired size or contour, and when relatively small dies are employed, the area of impact on the flexible sheets is localized at a 20 particular point, and may be placed at any particular portion of the area of the flexible sheets desired, without requiring that the impacted portion extend from edge to edge of the flexible material.

25 The flexible material sheets are thus secured together adequately, and either temporarily or permanently, without necessitating the use of complicated devices, and without requiring the use of external binding means, such as adhesives, 30 staples, pins, etc.

While the invention as disclosed herein is illustrated by a structure utilizing an impact or percussion arm and adapted to rest on an article of furniture, the invention may be utilized in a 35 variety of other forms, including devices adapted to be held by hand entirely, or mechanical operation may be utilized to actuate the moving arm or a solenoid may be used for that purpose, any such form coming within the scope of the present 40 invention as long as percussion or impact means is utilized for binding the paper or other flexible material together, without the use of extraneous bindings or binding means.

Having thus set forth my invention, I claim:
45 1. A device for binding superposed sheets of flexible material together, which device comprises two toothed members, the teeth of which are

adapted to intermesh, means for holding said toothed members in separated position, and means for impacting said toothed members together, the said teeth being of such depth as to cause a serrated distortion of the flexible material and an intermeshing of the fibers of the sheets together without tearing, whereby sheets of flexible material placed between said toothed members are bound together during the impacting 5 action.

2. A device for binding superposed sheets of flexible material together, which device comprises two toothed members, the teeth of which are adapted to intermesh, means for holding said toothed members in separated position, said 10 means including a fixed mounting for one of said toothed members and a movable mounting for the other of said toothed members, and means for impacting said toothed members together, the said teeth being of such depth as to cause a 15 serrated distortion of the flexible material and an intermeshing of the fibers of the sheets together without tearing, whereby sheets of flexible material placed between said toothed members are bound together during the impacting 20 action.

3. A device for binding superposed sheets of flexible material together, which device comprises two racks having teeth with rounded corners, the said teeth being adapted to intermesh, 30 means for holding said racks in separated position, including a fixed base member on which one of said racks is seated, and an arm carrying the second rack, said arm being pivotally mounted on said base member for arcuate movement 35 with respect thereto to bring the rack members into intermeshed position, whereby the arm may be impacted against the base to bind together sheets of superposed flexible material placed between said racks.

4. A device as set forth in claim 1, in which the toothed members are given a specific contour to produce an impact in a form selected from the group of letters, numerals and geometric figures.

45 RALPH M. HIBBS.
